BELL

Sajjan Singh Sarna, New York, N. Y.

Application February 4, 1952, Serial No. 18,354

Term of patent 3½ years

(Cl. D29—1)

To all whom it may concern:

Be it known that I, Sajjan Singh Sarna, a citizen of the United States of America, residing at New York, State of New York, have invented a new, original, and ornamental Design for a Bell, of which the following is a specification, reference being had to the accompanying drawing, forming a part hereof.

Figure 1 is a front elevational view of a bell showing my new design;

Figure 2 is a side elevational view thereof;

Figure 3 is a side elevational view thereof taken from the side opposite that shown in Fig. 2; and

Figure 4 is a top plan view thereof.

The opposite side of the bell to that shown in Fig. 1 is plain and has a lower edge indentation corresponding to the lower edge indentation shown in Fig. 1.

I claim:

The ornamental design for a bell, as shown and described.

SAJJAN SINGH SARNA.
